HEADER OR LIKE MECHANISM

Robert F. Mitchell, Watertown, and Erwin B. Byam, Wollcott, Conn., assignors, by mesne assignments, to Textron Inc., Providence, R.I., a corporation of Rhode Island

Filed Apr. 13, 1956, Ser. No. 578,071

3 Claims. (Cl. 74—38)

This invention relates to a header or like mechanism and more particularly to a machine for heading bolts or the like after a workpiece or blank has been cut from a length of rod stock. As illustrated the invention is applied to a two-blow machine for this purpose wherein a pair of punches are supported upon a reciprocable gate, and the punches are shifted from side to side in synchronism with the movement of the gate to align one punch with the die of the machine upon one stroke and the second punch with the die on the succeeding stroke, it being understood that the machine is provided with a single die.

It is contemplated by the invention to provide a machine of this character wherein the movable gate which carries the punches is operated by a toggle mechanism, the toggle being opened and closed by a main crank shaft extending transversely of the bed of the machine and located below the toggle links. By this arrangement the crank shaft which is a usual source of vibration due to the eccentric throw of the crank is placed at a low point with respect to the floor, and hence the moment of the vibrating force is reduced.

The construction of the toggle mechanism is such that the heading pressures are taken up by the toggles and not transferred to the crank shaft. Thus the crank shaft may be mounted on roller bearings and driven at a higher speed than is possible in machines wherein the crank is connected directly to the gate. In addition the gate is relatively wide and the punches are shifted in a horizontal direction across the front of the gate, and novel means are provided for effecting the shifting of the punches.

In addition to the above the improvements have been made in other features of the machine such, for example, as the toggle bearings, the construction of the gate, and the wire stop and cut-off mechanism, which will be described more particularly hereinafter.

One object of the invention is to provide a new and improved header mechanism which may be operated at a relatively high speed.

A still further object of the invention is to provide a header or like machine wherein the gate is operated by a toggle mechanism, the toggle being actuated by a crank shaft mounted at a position adjacent the base of the machine or floor so as to lessen the vibration due to the operation of the machine.

A further object of the invention is to provide a header of the class described wherein a bushing or roll is provided between the toggle arms to apply the pressure to these arms upon the operative strokes of the machine and to provide improved means for shifting the punches on the gate in a horizontal direction during the reciprocation of the gate.

To these and other ends the invention consists in the novel features and combinations of parts to be herein-after described and claimed.

In the accompanying drawings:

Fig. 1 is a top plan view of a header embodying our invention;

Fig. 2 is a sectional view on line 2—2 of Fig. 1;

Fig. 3 is a detail view of one of the toggle arms with the mating arm being shown in dotted lines; and

Fig. 4 is a side elevational view of the toggle arm shown in Fig. 3.

To illustrate one embodiment of the invention, there is shown in the drawings a header having a bed or frame 10 upon the forward portion of which is mounted a die bed 11 (Fig. 2) carrying a die 12 having a die opening 13 adapted to receive the work.

A knock-out rod 14 is mounted in the die bed in the usual manner, this rod being operated by a lever 15 from a rod 16 which may be reciprocated in the usual manner. Also mounted on the bed of the machine (Fig. 1) is a pair of feed rolls 17 adapted to be operated in any approved manner to feed the rod stock 19 through the face of the die block against a feed stop member 21.

The feed stop 21 comprises a horizontal arm 23 extending forwardly over the bed and provided with elongated openings 24 through which may be passed screws 25 to adjustably secure the stop to a block 26 secured to the bed. The position of the feed stop may be accurately adjusted by means of the adjusting screw 27 which bears against the same and which is threaded through a lug 28 secured to the block 26.

The gate is shown at 30 in Fig. 2 and is mounted upon a gate carrier slide 51 to which it is secured and keyed by the key 52. This slide is secured to a pair of rods 53 which are slidably mounted in bearings 54 and 55 in the bed. As shown in Fig. 1, these rods are spaced a substantial distance apart so that the gate carrier, which itself is relatively wide, has a broad bearing in the frame.

The gate is actuated from the crank shaft 56 (Fig. 2) which carries the crank 57. It may also be noted at this point that this crank shaft drives the side shaft 58 through the bevel gears 59.

A connecting rod 60 (Fig. 2) is mounted upon the crank 57, the upper end of which is bifurcated so as to provide spaced ears 61 (Fig. 1) through which extends a pin 62 which operates the toggle mechanism to be hereinafter described.

The toggle mechanism which operates the gate comprises the two toggle arms 63 and 64, the arm 63 being pivotally connected to the gate by the pin 65 and a bushing 66 is disposed between the pin and the adjacent surface of the socket 67 in the gate in which the end of the toggle arm is received. It will be understood that the pin 65 has a relatively loose fit in the end of the toggle arm so that the latter will abut the bushing 66 upon the operative or power stroke of the gate and relieve pressure from the pin 65.

Similarly the toggle arm 64 is pivotally connected by the pin 68 to a block 69 adjustably mounted on the bed as will be hereinafter described, this block being provided with a socket 70 having a bushing 71 therein similar to the bushing 67 previously described in connection with the toggle arm 63. Here again the pin 68 has a relatively loose fit in the toggle arm 64 so that the end of the toggle arm will contact the bushing upon the power strokes of the toggle mechanism.

The block 69 is connected to the bed by means of a screw 72 which passes through an elongated opening 73 in a part of the bed and is threaded into the block. The latter may be adjusted by means of the wedge 74 mounted between the rear beveled edge of the block 69 and a portion 75 of the bed. The wedge may be moved in a vertical direction by means of the adjusting screw 76 so that the block 69 may be moved forwardly and

rearwardly with respect to the bed in order to adjust the final forward position of the gate and the punches carried thereby. The block 69 may be drawn against the forward edge of the wedge 74 by the screws 77.

As shown more especially in Fig. 3, the toggle arm 63 is bifurcated at its rear end to provide spaced knuckles 79 which are received between corresponding knuckles 80 provided upon the rear toggle arm 64, and the pivot pin 62 passes through these knuckles. Also the toggle arms are provided with intermediate web portions 81 and 82, these portions being provided with arcuate sockets 83 and 84 (Fig. 2). Within these sockets are mounted bushings 85 and 86, and a roll 87 embraces the pin 62 and fits snugly against the bushings 85 and 86.

The pin 62 has a relatively loose fit in the roll 87 so as to take the strain from this pin on the power strokes of the toggle mechanism, the force being transmitted from the roll directly to the toggle arms to advance the gate.

It will be apparent that the gate is advanced twice during a complete stroke of the connecting rod 60 (that is upon a complete rotation of the crank shaft 56) as it will be advanced and withdrawn once upon the down stroke of the connecting rod and again upon the up stroke of the connecting rod. Also it may be noted that at the upper position of the toggle pin 62, shown in Fig. 2, it is at a slightly greater distance from the line joining the pins 65 and 68 than when the pin 62 is at its lowermost position. Thus the first or coning stroke of the gate is somewhat longer than the second or heading stroke.

As illustrated, two punches 88 and 89 are carried upon the gate, these punches being mounted upon punch holders 90 and 91 which are in turn adjustably secured to a carrier member 92 (Fig. 2). This carrier is slidably mounted to move transversely of the gate in a horizontal direction by means of the dovetailed member 93 secured to the carrier and held against the front of the gate by the gibbs 94 and 95.

With the present construction it has been found expedient to mount the crank shaft 56 upon roller bearings in the bed. In this manner the shaft can be driven at a relatively high speed, this being possible by reason of the toggle operation of the gate, as a result of which the reaction to the thrust of the gate is borne by the toggle mechanism and not by the crank shaft as would be the case if the latter acted directly upon the gate.

While we have shown and described one embodiment of our invention, it will be understood that it is not to be limited to all of the details shown, but is capable of modification and variation within the spirit of the invention and within the scope of the claims.

What we claim is:

1. Toggle mechanism connecting two relatively movable members, said mechanism including a pair of pivoted toggle links to effect reciprocation of one of said members, a pivot pin connecting the adjacent ends of

said links, means connected to the pivot pin to actuate the toggle mechanism, the outer end of one toggle link being pivoted to one member, and the outer end of the other toggle link being pivoted to the other member, each of said toggle links having spaced arms provided with openings through which said pivot pin extends, and also being provided with a web portion between said arms, and a member loosely mounted on said pivot pin with which said web member snugly engage to force said links outwardly when said pivot pin is actuated.

2. Toggle mechanism connecting two relatively movable members, said mechanism including a pair of pivoted toggle links to effect reciprocation of one of said members, a pivot pin connecting the adjacent ends of said links, means connected to the pivot pin to actuate the toggle mechanism, the outer end of one toggle link being pivoted to one member, and the outer end of the other toggle link being pivoted to the other member, each of said toggle links having spaced arms provided with openings through which said pivot pin extends, and also being provided with a web portion between said arms, a member loosely mounted on said pivot pin with which said web members snugly engage to force said links outwardly when said pivot pin is actuated, said member comprising a cylindrical roller mounted rotatably on said pin between said arms, and said web members having socketed end portions engaging the periphery of said roller.

3. Mechanism as set forth in claim 2 wherein the outer end of each of said toggle links is connected to the associated member by means of a pivot pin and each of said members is provided with a socket receiving the outer end of the associated toggle link, and a bushing is mounted in each of said sockets to abut the end of the toggle arm seated therein to transmit force from the toggle arm to said member and relieve pressure upon the pivot pins.
